SAFETY BLOCK FOR MINE CARS

Filed Feb. 23, 1929

C. F. Keck, INVENTOR

BY *Victor J. Evans*

ATTORNEY

UNITED STATES PATENT OFFICE

CARL F. KECK, OF PLEASANT UNITY, PENNSYLVANIA

SAFETY BLOCK FOR MINE CARS

Application filed February 23, 1929. Serial No. 342,118.

This invention relates to a safety block for mine and other cars, the general object of the invention being to provide means for chocking a pair of wheels of a car, with means whereby the device can be easily and quickly placed in position without the use of bolts, clamps or other fastening means, due to the peculiar shape of the rail engaging members which automatically adjust themselves on the tread portions of the rails to stop a car when a pair of wheels of the car strike said members.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:—

Figure 1 is a sectional view through a track, showing the invention in use.

Figure 2 is a plan view of Figure 1.

Figure 3 is a detail view showing a wheel in engagement with one of the track members.

Figure 4 is a perspective view of the device.

Figure 5 is a section on line 5—5 of Figure 4.

In these views, the numeral 1 indicates a flat bar of such a length that it will extend beyond the two rails of a track when the device is in use, with one end extended to form a handle 2. A pair of rail engaging members 3 have their horizontal portions 4 suitably fastened to the bar, with their rail engaging portions 5 extending upwardly at a slight inclination. The upper part of each portion 5 is formed with a head 6 having a substantially flat under face 7 which slopes upwardly and rearwardly from the front end of the head, so that the front end of the head has greater thickness than the rear end.

An upstanding flange 8 is formed on the front end of the head and a depending part 9 is formed on the free edge of the head so

as to provide a space between itself and the part 5 in which the tread part of the rail fits. An upstanding flange 10 is formed on the free edge of the head, this flange being diagonally arranged and forms a groove 11 between itself and the head. This flange 10 and the groove act as derailing means if the wheel should pass over the flange 8, as the flange of the wheel will pass into the groove 11 and thus be deflected by the flange 10 and said groove to the outside portion of the head so that the wheel will pass from the rail and thus the car will be derailed. The flange of the opposite wheel would, of course, pass the inner portion of the part 5 as said opposite wheel followed the movement of the first wheel. The head of the member engaged by said opposite wheel is provided with a notch 12 at the front end of the inner part of the head to receive a part of the flange of the wheel so that the tread portions of both wheels will strike the front ends of the heads 6 at the same time and thus keep the car squarely on the track. The derailing parts of the left hand member may be omitted, as, of course, these derailing parts are not necessary on this member.

As will be seen, when the wheels of a car strike the two members 5, the device will be tilted to the position shown in Figure 3, so that the flat part 7 will rest squarely on the tread of the rail. The enlarged front ends of the heads 6 of the rail engaging members will act to stop the car, but if the momentum of the car is too great, the derailing feature will come into action and thus derail the car.

It is simply necessary to hold the device by the handle 2 and push it under the rails, just behind a tie and then give it a twist in the direction of travel of the car so that the heads will engage the tread portions of the rails. The device is then in place and will act to stop or derail a car, as before described. The device will instantly adjust itself in place and is held in place by the peculiar arrangements of the head parts and the device can be easily and quickly removed.

It is thought from the foregoing description that the advantages and novel features of the invention will be readily apparent.

It is to be understood that changes may be made in the construction and in the combination and arrangement of the several parts, provided that such changes fall within the scope of the appended claims.

5 What I claim is:—

1. A device of the class described comprising a bar having a handle at one end thereof, a pair of upright members connected with the bar and a rail engaging head on the 10 upper end of each member having a large front end acting as a stop for the wheel of a car.
2. A device of the class described comprising a bar having a handle at one end thereof, 15 a pair of upright members connected with the bar, a head on each member having a channel in its under face for receiving the tread part of a rail, the front end of each head being enlarged to form a chock for the 20 wheel of a car, and derailing means carried by one of said members.
3. A device of the class described comprising a bar, a pair of upright members connected with the bar, heads having one side 25 thereof connected with each upright member, a depending part at the other side of each head and forming with the upper end of each member a space to receive the tread part of a rail, and an upright flange at the 30 front of each head.
4. A device of the class described comprising a bar, a pair of upright members connected with the bar, heads having one side 35 thereof connected with each upright member, a depending part at the other side of each head and forming with the upper end of each member a space to receive the tread part of a rail, and an upright flange at the 40 front end of each head, the under face of each head sloping upwardly and rearwardly from its front end.
5. A device of the class described comprising a bar having a handle at one end thereof, 45 a pair of upright members connected with the bar, heads having one side thereof connected with each upright member, a depending part at the other side of each head and forming with the upper end of each member a space 50 to receive the tread part of a rail, an upright flange at the front of each head and a diagonally arranged flange extending upwardly from the free edge of one of the members, with a groove in the head at the base of 55 the flange, said groove and flange forming derailing means.

In testimony whereof I affix my signature.
CARL F. KECK.
